UNITED STATES PATENT OFFICE

FRANK W. EDWARDS, OF CHICAGO, ILLINOIS, ASSIGNOR TO THE OHIO INJECTOR COMPANY, OF CHICAGO, ILLINOIS, A CORPORATION OF ILLINOIS

LOCKING DEVICE FOR ROTATABLE MEMBERS

Application filed October 6, 1930. Serial No. 486,803.

This invention relates to a locking device or rotation-arresting means for rotatable members, such, for example, as the filler-caps of lubricator oil bowls, in which connection it 5 will be hereinafter particularly described.

The oil bowls of lubricators, such as are used upon locomotives and other machines subjected to vibration, have their filling openings provided with closure caps or filler caps 10 which are ordinarily screwthreaded into the openings so that they may be securely fixed in place after the oil bowl has been filled. But, it has been found that, even when a filler cap is thus securely attached, the vibration 15 of the machine to which the lubricator is applied will result in the loosening and unscrewing of the cap and its displacement from the filling opening, thus sometimes resulting in loss of lubricant, loss of the filler cap, and 20 exposure of the interior of the oil bowl and the lubricant therein to dirt, dust and other deleterious foreign matter.

The object of this invention is to provide means whereby when the filler cap is secured 25 in place, it will not be possible for it to rotate or unscrew to such an extent that it may become displaced from the filling opening and lost, these means being such that they will operate substantially automatically and 30 not require any special attention.

The invention consists in locking or rotation-arresting means for rotatable members, such, for example, as filler caps, comprising a member carried by the rotatable member 35 and swingable laterally thereof under the influence of gravity to a position in which it may foul against some adjacent protruding part and thus arrest rotation of the member and lock it to the body to which it is applied, 40 thus preventing displacement and loss of the member, as will be hereinafter more particularly explained and finally claimed.

In the accompanying drawing illustrating the invention, in the several figures of which like parts are similarly designated, Figure 1 is an end elevation of a conventional form of lubricator having a filler cap provided with the device of the invention. Fig. 2 is a plan view of the parts shown in Fig. 1. 45 Fig. 3 is a detail side elevation of the filler

cap removed and illustrating the manner of applying the locking or rotation-arresting device thereto. Fig. 4 is an axial sectional view of the filler cap. Fig. 5 is an axial sectional view of the cap taken in a plane at 55 right angles to that of Fig. 4. Fig. 6 is a view similar to Fig. 4 but illustrating a modification.

The oil bowl 1 of the lubricator has in its top 2 a hollow neck 3 providing a filling opening closed by the filler cap 4, which latter is also herein referred to generically as a rotatable member. In the form shown, the cap 4 is provided with a screwthreaded extension 5 adapted to cooperate with the complementally screwthreaded interior of the filling opening neck 3, whereby the cap may be secured firmly in the opening. The cap is provided also with a flange 6 adapted to seat upon the upper edge of the neck 3, and with 70 a hexagonal or other shaped extension 7 whereby the cap may be applied or removed by means of a wrench.

The top of the cap 4 is provided with a boss, either integral as shown at 8 in Figs. 4 and 5, or as a separate screwthreaded or otherwise rigidly applied member 9, as shown in Fig. 6, and this boss is formed with a transverse bore 10 in which is hinged or pivoted or swingingly mounted the locking device 80 proper. This locking device is in the form of a relatively rigid rod bent to L shape, as shown in Fig. 3 with one end passed through the bore 10 and then bent to U shape to provide two outwardly extending legs 11 capable of a swinging movement under the influence of gravity from the position shown in Figs. 4, 5 and 6 to approximately that shown in Figs. 1 and 2.

In other words, with the legs 11 of the locking device in a position substantially axial of the cap 4, the cap may be screwed into or unscrewed from the filling opening. When the oil bowl has been filled and the filler cap 4 screwed tight to its seat upon the neck 3, 95 the locking device may be permitted to drop and its legs 11 will, by gravity, assume a position wherein they extend laterally of the cap 4 and probably bear against the top 2 of the oil bowl.

Lubricator oil bowls generally have upon their upper surfaces some projections. In the instance shown, a casing 12, which houses some adjusting mechanism, projects out of the plane of the top 2 of the oil bowl.

Obviously, if, from vibration or other cause, the cap 4 should start to unscrew, the legs 11 would encounter or foul against this projection 12 and would arrest the unscrewing movement of the cap.

It will thus be seen that the U-shaped locking device operates substantially automatically. It requires no setting or adjustment by the attendant, and so long as it is permitted to drop into its laterally extending position, which it will do as a matter of course, it will function to arrest rotation of the cap, as desired. Moreover, in order to release the device so that the cap may be unscrewed, it is only necessary to raise the legs 11 to substantially the position shown in Figs. 4, 5 and 6 relatively axially of the cap.

Although the locking device is shown as of U shape, and this is a preferred and convenient form both from a manufacturing and assembling standpoint and from a standpoint of low cost, it is to be understood that it may take a variety of shapes, so long as it is hingedly or swingingly carried by the rotatable member and may assume a position relatively thereto such that it may foul against some relatively fixed projection to arrest rotation of the member and thus lock it in position.

If desired, the usual breather port 13 may be provided in the cap 4, this port communicating with atmosphere through the transverse bore 10.

Various changes and modifications are deemed to be within the spirit of the invention and the scope of the following claims.

What I claim is:—

1. A locking device for rotatable members, comprising a substantially U-shaped gravity-responsive member pivotally connected to said rotatable member and swingable to a position laterally thereof and adapted to foul against some part adjacent to the rotatable member to arrest rotation of the rotatable member.

2. A locking device for the rotatable filler cap of an oil reservoir, comprising a swingable member carried by the cap and gravity influenced to assume an angular position relative to the axis of rotation of the cap, and offstanding laterally from the cap, said member when in this position adapted to foul against some projecting part of the reservoir to arrest rotation of the cap.

3. A locking device for the rotatable filler cap of an oil reservoir, comprising a swingable member carried by the cap and gravity influenced to assume an angular position relative to the axis of rotation of the cap and off-standing laterally from the cap, said member when in this position adapted to foul against

some projecting part of the reservoir to arrest rotation of the cap and said member capable of being positioned substantially in line with the axis of rotation of the cap whereby the cap may be rotated for application to or removal from the reservoir.

4. A locking device for rotatable members, comprising, in combination with an offstanding boss on the member, a relatively rigid rod pivotally connected with said boss and having its pivot arranged substantially normal to the axis of rotation of said member, said rod adapted normally to extend laterally of the rotatable member and to foul against some adjacent projection to arrest rotation of the member.

5. A locking device for rotatable members, comprising, in combination with an offstanding boss on the member, a relatively rigid rod passing through said boss and pivotally connected therewith and adapted normally to gravitate to a position laterally of the rotatable member and to foul against some adjacent projection to arrest rotation of the member.

6. A locking device for rotatable members, comprising, in combination with an offstanding boss on the member, a relatively rigid rod passing through said boss and bent to U shape and thus pivotally connected therewith and adapted normally to gravitate to a position laterally of the rotatable member and to foul against some adjacent projection to arrest rotation of the member.

7. A locking device for the rotatable cap of a lubricator oil bowl, including in combination with said cap and a projection on said bowl, a member hinged to said boss and gravity operated to assume a position wherein it will foul against said projection upon the occurrence of undesired rotation of said cap to arrest such rotation.

In testimony whereof I have hereunto set my hand this 3rd day of October, A. D. 1930.

FRANK W. EDWARDS.
